(57) **CLAIM**

The ornamental design for an ottoman, as shown and described.

DESCRIPTION

FIG. 1 is a front perspective view of a first embodiment of our design for an ottoman;

FIG. 2 is a front elevation al view thereof, the rear being a mirror image of the front;

FIG. 3 is a top plan view thereof;

FIG. 4 is a bottom plan view thereof;

FIG. 5 is a front perspective view of a second embodiment of the design for an ottoman;

FIG. 6 is a top plan view thereof;

FIG. 7 is a front perspective view of a third embodiment of our design for an ottoman;

FIG. 8 is a front elevation view thereof;

FIG. 9 is a front perspective view of a fourth embodiment of our design for an ottoman;

FIG. 10 is a front elevation view thereof; and,

FIG. 11 is a top plan view thereof.

The broken lines shown in the drawings are for illustrative purposes only and form no part of the claimed design.

The thick, broken away portions are understood to represent indefinite heights, lengths and/or diameters.
